UNITED STATES PATENT OFFICE

2,572,499

GRAPPLE

Frank J. Light, Sandusky, Mich.

Application January 21, 1948, Serial No. 3,611

1 Claim. (Cl. 294—107)

1

The present invention relates to new and useful improvements in grapples and more particularly to a device of this character for use in hoisting baled or loose hay, straw or the like, to a stack or in storing the same in barns or other buildings.

An important object of this invention is to provide a grapple to be used in conjunction with a conventional type of trip and hoist mechanism and including a main hoisting bar to which a plurality of oppositely extending grapple hooks are pivotally attached for grabbing engagement with the load by a hoisting movement of the bar and in which the hooks at each side of the hoisting bar are connected to each other for uniform engaging and releasing movements, whereby a trip device attached to the hooks will simultaneously release all of the hooks to drop the load.

A still further object is to provide an apparatus of this character of simple and practical construction, which is strong and durable, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view.

Figure 2 is a top plan view.

Figure 3 is an end elevational view showing the hooks raised for grappling a load.

Figure 4 is a similar view showing the hooks lowered in grappling position, and

Figure 5 is a fragmentary enlarged longitudinal sectional view of the central hoisting bar taken substantially on a line 5—5 of Figure 3.

Referring now to the drawings in detail wherein for the purpose of illustration, I have disclosed a preferred embodiment of the invention, the numeral 5 designates a central grapple bar having pairs of spaced apart collars or rings 6 secured thereto and at longitudinally spaced apart intervals. Each pair of collars is provided with a pivot pin 7 on which eyes 9 at the inner ends of oppositely extending jaws 10 are pivotally mounted, the jaws comprising substantially straight bars having downwardly and inwardly inclined prongs 11 at their outer ends.

Any desired number of the jaws 10 are carried by the central grapple bar 5, the present embodiment of the invention illustrating five pairs of such jaws.

2

Each of the jaws, adjacent the junction thereof with the prongs 11, is provided with an eye or loop 12 in which a connecting bar 13 is loosely positioned to connect all of the jaws at each side of the grapple bar 5 to each other for simultaneous raising and lowering movement while permitting the jaws 10 to spring laterally to facilitate embedding the prongs 11 in tightly packed bales of hay, or the like. Heads 14 are formed at the ends of the connecting bar 13 to limit endwise movement thereof in the eyes 12.

The central grapple bar 5 is provided with a pair of apertured hoisting rings 15 to which the ends of a hoisting rope or cable 16 are attached, the hoisting cable being raised and lowered by a conventional type of hoist mechanism (not shown).

Each of the connecting rods 13 are also provided with apertured ears 17 to which trip cables 20 or ropes 18 are attached, the cables 18 also being connected to a conventional type of trip mechanism (not shown), which may be used with a loading and unloading grapple of this character.

In operation of the device, the grapple is hoisted above the load, such as a number of bales of hay or the like indicated at 19 arranged in side by side relation, as shown in Figure 2 of the drawings and the grapple is then lowered and the prongs 11 imbedded in the respective bales.

The hoisting cable 16 is then pulled upwardly which raises the central grapple bar 5 and causes the prongs 11 to bite into the load. The prongs 11 may engage a group of end bales while one or more additional bales may be placed between the end groups of bales, as shown at 20, and without being grappled by one of the prongs, the prongs and hooks having a tendency to pull the end bales inwardly toward each other to grip the center bales 20 and thus hoist all of the bales.

The prongs 11 of the hooks are released by pulling on the trip cables 18 in the usual manner which thereby lifts the prongs from the bales to drop the load.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein

described and the scope of the appended claim.

Having described the invention what is claimed as new is:

A grapple comprising a central hoisting bar, pairs of collars secured to the bar at longitudinally spaced apart intervals, a pair of grappling hooks pivoted at their inner ends to each pair of collars and extending outwardly at opposite sides of the bar, aligned eyes on the hooks, and rods loosely positioned in the eyes to connect the hooks at each side of the grapple for uniform raising and lowering movement while permitting the hooks to spring laterally, said bar having a hoisting cable attached thereto, and said rods having releasing cables attached thereto.
